(57) **CLAIM**

The ornamental design for a light-emitting diode edge lighted airfield guidance sign, as shown and described.

DESCRIPTION

FIG. 1 is a perspective view of a light-emitting diode edge lighted airfield guidance sign, showing our new design;

FIG. 2 is a front elevation view thereof;

FIG. 3 is a back elevation view thereof;

FIG. 4 is a top view thereof;

FIG. 5 is a bottom view thereof;

FIG. 6 is a left-side elevation view thereof; and,

FIG. 7 is a right-side elevation view thereof.

The portions of the light-emitting diode edge lighted airfield guidance sign shown in broken lines in the drawings represent unclaimed subject matter and form no part of the claimed design.

1 Claim, 5 Drawing Sheets
